UNITED STATES PATENT OFFICE.

LUDWIG BURESCH, OF EMMETT, IDAHO.

SAW.

1,259,831.

Specification of Letters Patent. Patented Mar. 19, 1918.

Application filed March 21, 1917. Serial No. 156,267.

To all whom it may concern:

Be it known that I, Ludwig BURESCH, a subject of the Emperor of Germany, resident of Emmett, county of Gem, and State 5 of Idaho, have invented certain new and useful Improvements in Saws, of which the following is a specification.

This invention relates to improvements in carpenters' tools, and particularly to 10 hand-saws.

The principal object of the invention is to provide a saw having a straight back which may be graduated, if desired, so that 15 distances may be readily measured therefrom, and combined with the saw handle an upright element, forming, when in an erect operative position, an angle of 90 degrees whereby the saw blade may be used as a square.

20 A further object is to provide with such collapsible square, blade, means whereby it may be readily raised into operative position or collapsed within the handle so that no unsightly projection appears or interferes with the ordinary use of the saw.

These and other objects are attained by the novel construction and combination of parts hereafter described and shown in the 30 accompanying drawing, forming a material part of this specification, and in which:—

Figure 1 is a side elevational view of a saw showing the application of the invention.

Fig. 2 is an enlarged partial sectional view showing the blade in a raised or operative position, and

Fig. 3 is a similar view of the same showing the blade as received into the handle.

In the drawings, the numeral 10 is applied to the saw blade, which is of the usual construction, provided with teeth 11 upon its cutting edge, the back 12 being straight and provided with graduations 13 as indicated.

45 This blade is affixed in a handle 15, provided with an opening 16 through which the fingers of the operator enter, the handle being grasped principally by the bar 17, which is shaped and formed in all respects as is common, the blade being held

50 in the handle by means of rivets 18.

Within the handle is a substantially rectangular opening 20 arranged diagonally and having secured in a recess 21, a spring element 22 having a bent, hook-shaped end. 55

Extending outwardly through the slot 19, formed in one side of the handle, is a projection 24, by means of which the spring 22 may be retracted farther into the recess when desired.

60 A plate or blade 25, provided with graduations 26, is receivable within the recess 20, the blade having an angularly turned portion 27 at its lower end provided with an upturned toe element 28 engageable within 65 a corresponding recess 29 at the top of the opening 20, an indentation 23 being formed in the angular element 27, the same being adapted to engage with the hook or bent free end of the spring 22 when in an ex- 70 tended position.

A clip 30 is formed with the blade 25 by means of which the same may be withdrawn through the passage 31, leading to the opening 20, the projection 27 having a 75 flat portion 33 adapted to engage upon the seat 34, formed at the upper end of the opening 20, the seat being parallel with the back 12 of the saw blade.

In operation, when it is desired to extend 80 the square blade 25, the clip 30 is grasped by the fingers, the blade withdrawn through the passage 31, until the end of the spring 22 is engaged in the recess 23 at which time the angular projection 27 has become positioned on the seat 34, holding the blade securely at right angles with the saw-blade, the lower end of the square blade being seated against a shoulder 35, whereby it is positioned at the proper angle with respect 85 to the back of the saw-blade.

When not in use, the projection 24 is moved in the slot 19, the depression of the spring allowing the blade to be pressed backward into the opening 20 in an obvious 90 manner, and upon its release to hold the square blade from movement by its tension.

Having thus described my invention, what I claim as new, and desire to secure by Letters Patent, is:—

100 In a tool having a straight edge and a handle provided with a pocket arranged at

an angle with and adjacent to said straight edge, the combination of a blade adapted to be housed in said pocket, a lateral extension thereon for engagement with one wall 5 of said pocket to maintain said blade at right angles with said straight edge when

in extended position, and releasable means for maintaining said extension in engagement with said wall of said pocket.

In testimony whereof I have affixed my 10
signature.

LUDWIG BURESCH.
